UNITED STATES PATENT OFFICE.

VICTOR E. ADLER, OF LOS ANGELES, CALIFORNIA.

DESIGN FOR A RING FOR A BANJO.

Application filed July 15, 1926. Serial No. 18,364. Term of patent 3½ years.

To all whom it may concern:

Be it known that I, VICTOR E. ADLER, a citizen of the United States, residing at Los Angeles, in the county of Los Angeles and State of California, have invented a new, original, and ornamental Design for a Ring for a Banjo, of which the following is a specification, reference being had to the accompanying drawing, forming part thereof.

Figure 1 is a top plan view of a portion of a banjo illustrated in dotted lines to which the novel ring is illustrated as having been applied.

I claim:

The ornamental design for a ring for a banjo as shown.

VICTOR E. ADLER.
